[57] CLAIM

The ornamental design for a child recreation climber
structure, as shown and described.

DESCRIPTION

FIG. 1 is a perspective view of the child recreation
climber structure showing my new design;
FIG. 2 is a rear elevational view thereof;
FIG. 3 is a right side elevational view thereof, the left
side being substantially a mirror image thereof, and
FIG. 4 is a top plan view.*Fig. 2.*

*Fig. 3.**Fig. 4.*
